Primary Examiner — T. Chase Nelson*Assistant Examiner* — Mark Cavanna(74) *Attorney, Agent, or Firm* — Brinks Gilson & Lione(57) **CLAIM**

We claim the ornamental design for a chip for biochemical examination, as shown and described.

DESCRIPTION

FIG. 1 is a front perspective view of a chip for biochemical examination of the present invention;

FIG. 2 is a rear perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof;

FIG. 8 is a bottom view thereof;

FIG. 9 is a sectional view taken along the line 9-9 of FIG. 4;

FIG. 10 is a sectional view taken along the line 10-10 of FIG. 4;

FIG. 11 is a sectional view taken along the line 11-11 of FIG. 4;

FIG. 12 is a sectional view taken along the line 12-12 of FIG. 4; and,

FIG. 13 is a rear perspective view thereof with the cover removed.
The broken line showing of chip for biochemical examination is included for the purpose of illustrating environment and forms no part of the claimed design.**1 Claim, 13 Drawing Sheets****FIG. 1**
